UNITED STATES PATENT OFFICE.

LEVI J. LENNOX, OF DETROIT, MICHIGAN.

FOLDING BED.

No. 892,998.

Specification of Letters Patent.

Patented July 14, 1908.

Application filed September 23, 1907. Serial No. 394,064.

To all whom it may concern:

Be it known that I, LEVI J. LENNOX, a citizen of the United States of America, residing at Detroit, in the county of Wayne and State 5 of Michigan, have invented certain new and useful Improvements in Folding Beds, of which the following is a specification, reference being had therein to the accompanying drawings.

10 This invention relates to beds and to improvements in folding beds especially adapting them for use in hospitals and for invalids.

The invention consists in the matters hereinafter set forth, and more particularly pointed out in the appended claims.

15 Referring to the drawings, Figure 1 is a plan view of a bed embodying features of the invention. Fig. 2 is a view in side elevation, partially broken away, showing the bed in 20 normal position. Fig. 3 is an end view of the bed. Fig. 4 is a view in side elevation of the bed in a folded position. Fig. 5 is an end view in detail of the bed-spring frame. Fig. 6 is a view in detail on line x—x of Fig. 5 of a 25 link and roller. Fig. 7 is a view in detail of a swing shelf on the bed. Fig. 8 is a view in detail of a pivot block for the shelf. Fig. 9 is a view in detail of a side bracket. Fig. 10 is a view in detail of a section upper hinge or 30 pivot joint.

As shown herein, a rectangular main-frame 35 preferably constructed of side angle irons 1 and end angles 2 properly connected at the corners, is pivoted off center by any suitable means, preferably ball tenons 3 detachably interlocking with sockets 4, to two-part end boards whose movable sections are adapted to fold inwardly against the frame when the latter is in upright position. In the preferred form herein illustrated, the stationary 40 sections of the boards each consist of a tubular corner post 5 inbent and suitably connected at its upper end as by a butt weld joint to a tubular upright 6, a cross brace 7 at the regulation height of a bed rail completing the frame. A stay rail 8 has end tenons 9 of any conventional type ordinarily used for side rails, detachably interlocking with mortise blocks 10 near the lower ends of 45 the uprights 6 out of vertical alinement with the sockets 4, so that the main-frame and stay rail maintain these sections in proper relation. The movable sections each consist of a corner post 11 bent to correspond to 50 the opposite post 5, a cross rail 12 whose inner end is shouldered and halved to the inner

end of the cross brace 7 to form an inwardly breaking hinge 13 of the rule-joint type, and a standard 14 which is stepped on the rail 12 in symmetrical relation to the upright 6, and is bent over and suitably pivoted to the upper end of the upright in axial alinement therewith, preferably by dropping over a pintle 15 inserted on the upright.

50 The projecting ends of a clamping rod 16 longitudinally movable in guide apertures in the end angle bars 2 beneath the horizontal flange of the main-frame enter segmental slots 17 in hanging brackets 18 secured on the outer posts of the head and foot boards 60 when the latter are extended. A head 19 on one end of the rod and a washer 20 on the other end may be forced toward each other by a suitable hand lever 21 which cams against the washer when depressed, or is 65 otherwise adapted to clamp the washer and head against the brackets. The contacting surfaces of the brackets, rod head and washer may be serrated or notched if desired, and a seat 22 for the head and washer 70 may be formed in each bracket for accurately locking the main-frame in horizontal position. A flange 23 on the bracket acts as a shield for the head or washer. The rod is released when the hand lever 21 is loosened, 75 by a spring 24 in compression between the end angle iron near the lever 21 and a block 25 secured on the rod whose movement toward the frame center is limited by a stop 26 on the under side of the side angle iron. When 80 the handle is of the form herein indicated, having a flattened rounded end 27 eccentrically centered by a pin 28 in a slot in the end of the bar, the block 25 may be adapted to bear laterally against the side angle iron and 85 hold the rod against rotating with the handle in convenient operating position.

85 A rectangular mattress or spring frame of side rails 29 preferably of angle iron, secured together by a head rail 30 and a foot rail 31, 90 likewise preferably of angle iron, is pivoted at the foot to the main-frame by bolts 32 or the like passing through the depending flanges of the side rails and of the side angle bars 1, which the side rails overlap closely when 95 closed thereon. The lower horizontal flange of the head rail 30 rests on a pair of friction rolls 33 journaled on studs 34 secured to arms 35 which are pivoted at their lower ends to the main-frame and articulated to 100 move in parallel relation by a horizontal link 36 having an outturned end or handle 37

- near the front side of the bed. By pulling the handle 37 toward the front of the bed until the arm rolls 33 are past the vertical line of the arm pivots and the arms engage a suitable stop 38 the mattress spring frame may be longitudinally tilted. A spring clip 39 on the side rail hooks over the main-frame when the upper frame is in its normally horizontal position.
- 10 A shelf 40 is pivoted to a pivot block 41 which slides on the clamping rod 16 and is held from rotation by engaging with the adjacent side angle. The shelf is adapted to turn completely under the frame, a forked 15 spring stop 42 snapping over the lower edge of the side angle 1 and locking the shelf in extended position when desired.

20 A mattress spring fabric of any preferred type may be conveniently secured to the upright flanges of the head and foot rails in any suitable manner.

25 In operation, the bed may be longitudinally inclined or not, and may be laterally tilted and clamped readily at an angle independently of its longitudinal position, from the front side of the bed. The bed may be raised and folded into small compass or may be readily taken apart for shipping or cleaning. Obviously the head and foot boards 30 may be of any ornamental design preferred.

35 One feature of the invention is the compactness of the frame, the superposed side angles of both frames closing by each other and the end angles lying back to back. Another feature is the grouping of the manipulating means at the front side of the bed so that the bed may be secured in the position desired without reaching over or otherwise disturbing an occupant. At the same time 40 the clamping rod and head raising lever do not project beyond the bed proper, and are practically concealed.

45 Obviously changes in the details of construction may be made without departing from the spirit of the invention and I do not care to limit myself to any particular form or arrangement of parts.

What I claim as my invention is:—

1. A folding bed comprising two part end 50 boards each consisting of a stationary section and a movable section hinged thereto to swing in a horizontal plane, a main-frame pivotally supported at each end on the stationary sections and adapted to be secured 55 in laterally tilted position to the movable sections when they are extended, and a spring frame longitudinally tilttable on the main-frame.

2. In a folding bed, a main-frame, two-part 60 end boards having stationary sections that pivotally support the ends and the main-frame, and movable sections that are hinged to the stationary sections to fold against the main-frame when it is upright and are adapt- 65 ed when extended to support the lowered

main-frame in a laterally tilted position, and a spring frame longitudinally tilttable on the main-frame regardless of the angular position of the latter.

3. In a folding bed, a main-frame, two part 70 end boards having stationary sections that pivotally support the ends of the main-frame, and movable sections that are hinged to the stationary sections to fold against the main-frame when it is upright and are adapted 75 when extended to support the lowered main frame in a laterally tilted position, a stay-rail detachably interlocked at each end with the stationary sections, and a spring frame longitudinally tilttable on the main-frame regardless 80 of the angular position of the latter.

4. In a folding bed, a main-frame, two part 85 end boards having stationary sections that pivotally support the ends of the main-frame and movable sections that are hinged to the 85 stationary sections to fold against the main-frame when it is upright and are adapted when extended to support the lowered main-frame in a laterally tilted position, a stay-rail 90 detachably interlocked at each end with the stationary sections, and a spring frame longitudinally tilttable on the main-frame regardless of the angular position of the latter.

5. In a folding bed, a main-frame, two part 95 end boards having stationary sections that pivotally support the ends of the main-frame and movable sections that are hinged to the stationary sections to fold against the main-frame when it is upright and are adapted when extended to support the lowered main-frame in a laterally tilted position, a stay-rail 100 pivotally supported on the main-frame to tilt longitudinally, and means to hold the stay-rail in tilted position independent of the position of the main frame.

6. In a folding bed, a main-frame, two part 105 end boards having stationary sections that pivotally support the ends of the main-frame and movable sections that are hinged to the stationary sections to fold against the main-frame when it is upright and are adapted when extended to support the lowered main-frame in a laterally tilted position, a stay-rail 110 pivotally supported on the main-frame to tilt longitudinally, and means to hold the stay-rail in tilted position independent of the position of the main frame.

6. In a folding bed, a main-frame having side angle irons connected by end angles, two part end boards having stationary sections 115 that pivotally support the ends of the main-frame and movable sections that are hinged to the stationary sections to fold against the main-frame when it is upright and are adapted when extended to support the lowered 120 main-frame in a laterally tilted position, and a spring frame having side rails of angle iron whose outer dependent flanges close over the outer dependent flanges of the main-frame and are pivoted thereto near one end by bolts passing through said flanges, longitudinally tilttable on the main-frame regardless of the angular position of the latter.

7. A folding bed comprising two-part end 125 boards each consisting of a stationary section and a movable section hinged thereto to swing in a horizontal plane, a rectangular frame detachably pivoted at its ends to the stationary sections to tilt laterally against which the movable sections are adapted to 130

be folded when the frame is upright, a slotted supporting bracket on each movable section, and a longitudinally movable spring projected headed rod on the frame adapted to enter the bracket slots, a washer on the rod and a clamping handle on the rod adapted to simultaneously force the head and washer against the brackets.

8. In a folding bed, two-part end boards each consisting of a stationary section and a movable section hinged thereto to swing in a horizontal plane, a rectangular frame pivoted at each end to the stationary sections to tilt horizontally consisting of side angle bars connected at their ends with similarly disposed end angle irons, supporting brackets on the movable sections provided with vertically disposed slots, a clamping rod longitudinally movable in guide apertures in the vertical flanges of the end angles adjacent a side angle, a block secured on the rod non-rotatively sliding on said side angle iron, a spring in compression between the block and the adjacent end angle, a head on one projecting end of the rod, a clamping handle on the other end and a washer adjacent the handle, projecting ends of the rods entering the bracket slots when the movable sections are extended and the frame downturned, and the handle being adapted to simultaneously force the head and washer into engagement with the bracket.

9. In a folding bed, two-part end boards each consisting of a stationary section and a movable section hinged thereto to swing in a horizontal plane, a rectangular main-frame

pivoted at each end to the stationary sections to tilt horizontally consisting of side angle bars connected at their ends with similarly disposed end angle irons, supporting 40 brackets on the movable sections provided with vertically disposed slots, a clamping rod longitudinally movable in guide apertures in the vertical flanges of the end angles adjacent a side angle, a block secured on the rod 45 non-rotatively sliding on said side angle iron, a spring in compression between the block and the adjacent end angle, a head on one projecting end of the rod, a clamping handle on the other end and a washer adjacent the 50 handle, the projecting ends of the rods entering the bracket slots when the movable sections are extended and the frame downturned, and the handle being adapted to simultaneously force the head and washer into 55 engagement with the bracket, a spring frame consisting of side rails of angle iron whose flanges close by the side flanges of the main-frame and are pivoted thereto at one end and end rails connecting the side rails, parallel 60 arms pivoted to one end angle iron of the main-frame, stud rollers thereon supporting the adjacent end rail of the spring frame, and a link articulating the arms whereby the arms may be moved into an upright position. 65

In testimony whereof I affix my signature in presence of two witnesses.
